FRANK W. LEWIS, OF DAVENPORT, IOWA, ASSIGNOR TO THE BETTENDORF COMPANY,
OF BETTENDORF, IOWA, A CORPORATION OF IOWA

BOLSTER MOUNTING

Application filed August 4, 1928. Serial No. 297,468.

This invention relates to bolster mountings and more particularly to spring supports for the ends of the bolsters of railway car trucks.

5 Truck bolsters are commonly mounted for vertical movement between suitable guide members carried by the truck frame and are supported at their ends upon suitably arranged groups of compression springs so that 10 the car body is yieldably supported upon the trucks and sudden variations in load due to irregularities in the track are in part absorbed by the bolster springs. The loads imposed on the spring seats which are mounted 15 on the tension chords of the side frame members of the truck cause severe bending strains tending to distort the frame.

It is an important object of the invention to provide tension chords of such form and a 20 spring mounting of such character that the original shape is less subject to distortion.

Lateral movements of the bolster in its guides due to increase or decrease in rate of 25 travel may cause a very considerable frictional resistance to vertical movements of the bolster with the result that shocks may be transmitted directly to the truck frame instead of through the springs due to binding of the bolster in its guides.

30 It is an object of the present invention to provide a mounting for the bolster in which some of the bolster supporting springs are so mounted that they perform the dual function of sustaining the vertical load and taking 35 up shocks and strains tending to move the bolster longitudinally of the side frame members and which permits substantially free vertical movements of the bolster and greatly reduces frictional interference between the 40 bolster and its guides, thereby greatly increasing the effectiveness of the bolster supporting springs in cushioning the shocks imposed on the bolster.

A further object of the invention is to provide a car truck in which the side frame members are stronger and capable of carrying greater loads than side frame members of conventional design.

45 A further object of the invention is to provide a spring mounting for bolsters which is

applicable to practically all of the various types of railway car trucks now in use and which may be embodied in the various bolster spring groupings employed in such trucks.

With the above and other objects in view, 55 the invention may be said to comprise a bolster mounting as illustrated in the accompanying drawings hereinafter described and particularly set forth in the appended claims, together with such variations and modifications thereof as will be apparent to one skilled 60 in the art to which the invention appertains.

Reference should be had to the accompanying drawings forming a part of the specification in which:

65 Figure 1 is a fragmentary top plan view showing a portion of one side of a railway car truck to which a bolster mounting embodying the invention has been applied.

Fig. 2 is a side elevation of the portion of 70 the car truck shown in Fig. 1.

Fig. 3 is a section taken on the line indicated at 3—3 in Fig. 1.

Figs. 4 and 5 are a fragmentary plan view and side elevation, respectively, showing the 75 invention applied to a bolster mounting in which a different grouping of springs is employed.

Figs. 6 and 7 are a top plan view and side elevation, respectively, showing the invention 80 applied to a bolster mounting in which still another arrangement of springs is employed.

Figs. 8 and 9 are a top plan view and side elevation, respectively, showing the invention applied to a bolster mounting having a further modification of the spring grouping.

85 Figs. 10 and 11 are a top plan and side elevation, respectively, showing the invention applied to a bolster mounting similar to that shown in Figs. 8 and 9, but with the springs 90 arranged somewhat differently.

Fig. 12 is a side elevation showing the invention applied to a bolster mounting of the type in which the bolster is carried by a support which has a limited turning movement 95 in the side frame members of the truck.

In Figs. 1, 2 and 3 of the drawing, the invention is shown applied to a railway car truck which has side frame members 1 of truss form which are supported at their ends 100

on the axles of wheels 2. Each of the side frame members 1 has an upper or compression chord 3 and a lower or tension chord 4 and these chords are connected by spaced columns 5 formed integrally therewith, the columns 5 and spaced chords 3 and 4 forming a bolster receiving opening 6 which is wider adjacent the bottom thereof than adjacent the top to permit insertion of the bolster, the upper portions of the columns 5 being formed to provide vertical guide portions 7 for a transverse bolster 8. The bolster 8 is provided with laterally projecting guide ribs 9 which overlie the inner and outer faces of the guide portion 7 of the columns to limit the endwise movements of the bolster.

The bolster 8 has its bottom formed adjacent the ends thereof to provide seats for supporting springs, the central portion 10 of the bottom face of the bolster being flat and lying substantially in a horizontal plane. On opposite sides of the central portion 10, the bottom face of the bolster is inclined upwardly to provide oppositely inclined seats 11.

I have discovered that if the intermediate portion of the tension chord of the side frame member is downwardly cambered instead of straight and horizontally disposed, the side frame member is stronger and capable of carrying greater loads than side frame members of conventional design. The construction of the intermediate portion of the tension chord in this manner has the further advantage of providing spring seats which are so disposed with relation to the bolster that some or all of the springs depending on the number used, may be so disposed with respect to the bolster as to take up shocks exerted on the bolster which tend to move the bolster longitudinally of the frame member and transversely of the bolster guides thereby holding the bolster centered in the bolster opening.

The intermediate portion of the tension chord 4 extending across the bottom of the bolster opening 6 is downwardly cambered to provide a support for a metal plate 12 which serves as a spring seat. The spring seat 12 conforms to the downwardly cambered intermediate portion of the chord 4 and has a central portion 13 directly beneath the central seating portion 10 of the bolster, which is horizontally disposed and on opposite sides of the central portion 13 has upwardly inclined seating portions 14 which are disposed substantially parallel with the inclined seating portions 11 on the bottom face of the bolster. Vertically disposed coil springs 16 are interposed between the horizontal seating portion 10 of the bolster and the horizontal portion 13 of the spring seat, and laterally inclined coil springs 16 are interposed between the inclined seating portions 11 on the underside of the bolster and the inclined portions 14 of the spring seat.

As shown in Figs. 1, 2 and 3, the springs

are arranged in two rows extending longitudinally of the side frame member, two of the springs being vertically disposed beneath the longitudinal axes of the bolster and two springs being interposed between the inclined seating portions of the bolster and seat on each side of the central vertically disposed springs. The opposite inclination of the springs 16 on opposite sides of the central axis of the bolster causes these inclined springs to exert lateral thrusts in opposite directions upon the bolster and since the springs are of substantially equal strength and are disposed at equal and opposite inclinations, the lateral thrusts in one direction are counter-balanced by the lateral thrusts in the opposite direction and the oppositely inclined springs tend to hold the bolster in a central position with respect to the guides 7 and prevent lateral movements of the bolster which cause frictional interference between the bolster and guides. The bolster is thus caused to move vertically between the guides substantially without frictional resistance so that the springs are permitted to exert their full cushioning effect when sudden increases in the load are transmitted to them through the bolster so that the truck frame members are relieved of severe stresses which would otherwise be imparted to them by frictional engagement of the bolster in its movements up and down within the frame members.

It should be noted that the tension chord 4 has a general curvature conforming to the upper spring seating surface thereof, the chord 4 having its lowest portion beneath the central seat 13 and being inclined upwardly beneath the inclined seats 14. The shape of the chord 4 is substantially that which the chord would tend to assume under load, so that the tendency of the frame to be distorted under load is reduced to a minimum.

In Figs. 4 and 5 of the drawing, there is shown a modified bolster mounting in which a side frame member is provided with a relatively wide bolster opening 21 to receive the widened end 22 of the bolster, the widened end 22 being provided with guide ribs 23 similar to the guide ribs 9 above described and overlying the opposite faces of the frame member along the opposite sides of the bolster opening 21.

The widened end 22 of the bolster has a bottom face formed to provide a central horizontal seating portion 24 and upwardly inclined seating portions 25 on opposite sides of the seating portion 24. The frame member 20 is formed to provide a support across the bottom of the bolster opening 21 for a steel plate 26, which forms a spring seat. The spring seat 26 has a central portion 27 which lies directly beneath the central portion 24 on the under side of the bolster and upwardly inclined side portions 28 which are substantial-

ly parallel with the inclined seating portions 25 on the underside of the bolster.

In this modification, the centrally disposed horizontal seating portions 24 and 27 of the bolster and spring seat are relatively wide to provide spaces to receive four vertically disposed supporting springs 29 and on opposite sides of the central supporting springs 29 are inclined springs 30 interposed between the inclined seating portions 25 and 28 of the bolster and spring seat, a single spring 30 being provided at each end of the spring seat, the inclined springs 30 serving the same purpose as the inclined springs 16 in the arrangement first described, and the tension chord being shaped similarly to the chord shown in Figs. 1, 2 and 3 to reduce the bending stresses.

In Figs. 6 and 7 of the drawing, there is shown a side frame member 31 which is provided with a relatively narrow bolster receiving opening 32 in which the end of a bolster 33 is slidably mounted. The under face of the bolster 33 has oppositely inclined seating portions 34 which converge to the longitudinal center line of the bolster. At the bottom of the bolster opening 32, there is mounted a spring seat 35 which has oppositely inclined side portions 36 which converge to the center line of the seat which is directly beneath the center line of the bolster. Oppositely inclined compression coil springs 37 are interposed between the oppositely inclined seating portions 36 of the spring seat 35 and the oppositely inclined seating portions 34 on the under side of the bolster. The oppositely inclined springs 37 being arranged in two parallel rows extending longitudinally of the bolster and transversely of the side frame members, all of the supporting springs in this modification being inclined, one-half of the total number of springs being inclined in one direction and the other half thereof in the opposite direction.

In this modification, also, the curvature of the tension chord conforms to the inclination of the seats so that the loads are supported with a minimum of bending stresses in the chord.

In Figs. 8 and 9 of the drawing, there is shown a spring mounting in which the springs are arranged in a circular group. In this modification, a side frame member 40 is provided with a bolster receiving opening 41 in which the bolster 42 is slidably mounted. The bolster has on its under face, a central horizontally disposed seating portion 43 and on opposite sides of the horizontal central portion, upwardly inclined seating portions 44. At the bottom of the bolster receiving opening 41, there is mounted a spring seat 45 which has a central horizontal portion 46 and upwardly inclined seating portions 47 on opposite sides of the central seating portion 46.

Three vertically disposed supporting

springs 48 are arranged in a row between the horizontal seating portions of the bolster and a spring seat and on each side of this central row, are arranged two laterally inclined springs 49 which rest at their lower ends on the inclined portions 47 of the spring seat and bear at their upper ends against the inclined seating portions 44 of the bolster. The centers of the springs 49 being arranged midway between the centers of the middle and end springs of the central row so as to provide a substantially circular grouping of six springs about a central spring.

Figs. 10 and 11 of the drawing show a spring mounting in which the springs are grouped in a manner similar to that shown in Figs. 8 and 9, except that in this modification, only two of the springs have lateral inclination. In this modification, a frame member 50 is provided with a bolster receiving opening 51 in which the end of the bolster 52 is slidably mounted. The bolster 52 has on its under face, a central horizontal seating portion 53 and inclined seating portions 54 on opposite sides of the seating portion 53. At the bottom of the bolster opening 51, there is a spring seat 55 which has a central horizontal portion 56 and inclined seating portions 57 on opposite sides of the central seating portion 56. Five supporting springs 58 are disposed vertically and interposed between the horizontal seating portions of the bolster and spring seat and a single spring 59 is interposed between the inclined seating portions 54 and 57 at each side of the horizontal seating portions of the bolster and spring seat. In this modification, the circularly grouped springs are arranged so that there is a central row of three springs extending longitudinally of the side frame member instead of longitudinally of the bolster as in the modification shown in Figs. 8 and 9, the end springs of this central row being the springs which are set at an inclination.

Fig. 12 of the drawing shows the invention applied to a bolster mounting of the type in which a bolster support is provided which is mounted in the side frame members for limited angular movement to permit the bolster to have a slight lateral rocking movement. In this modification, a frame member 60 has rotatably mounted therein, a bolster carrying member 62 which is provided with vertically disposed guides 63 between which the bolster 64 may move vertically. The bolster 64 has on the bottom face thereof oppositely inclined seats 65 and the supporting member 62 carries a spring seat 66 beneath the bolster which has inclined seating portions 67 substantially parallel with the inclined seating portions 65 of the bolster.

Inclined springs 68 are interposed between the inclined seating portions 65 of the bolster and 67 of the spring seat, these springs acting

in the same manner as the laterally inclined springs in the modification above described to center the bolster with respect to its guides and prevent frictional interference with the movements of the bolster.

5. In each of the modifications above described, bolster supporting springs which are oppositely inclined tend to maintain the bolster in a central position with respect to its 10 guides and substantially free from frictional engagement therewith so that the bolster may move freely between its guides and transmit the loads to the truck through the springs, thereby relieving the truck frame of the excessive stresses caused by binding of the bolster in its guides.

Furthermore, it is to be understood that the particular form of apparatus shown and described, and the particular procedure set forth, are presented for purposes of explanation and illustration and that various modifications of said apparatus and procedure can be made without departing from my invention as defined in the appended claims.

25. What I claim is:

1. In a railway car truck having a yieldably supported bolster, vertical guide members on opposite sides of the bolster, a spring seat beneath the bolster, and oppositely inclined compression coil springs interposed between the bolster and seat.

2. In a railway car truck having a transverse bolster, which has oppositely inclined faces on the under side thereof, vertical guide members on opposite sides of the bolster, a spring seat beneath the bolster having faces substantially parallel with the inclined faces of the bolster, and supporting springs interposed between the substantially parallel faces of the bolster and seat.

3. In a railway car truck having a transverse bolster, said bolster having a bottom face provided with a central horizontally disposed portion and side portions inclined upwardly from said central portion, a spring seat beneath the bolster and having a horizontally disposed central portion and upwardly inclined side portions, springs interposed between the horizontal central portions of the bolster and seat, and springs interposed between the inclined portions of the bolster and seat.

4. In a railway car truck having a transverse bolster, a side frame member having a bolster receiving opening in which an end of the bolster is mounted for vertical movement, a spring seat supported upon the bottom of said bolster opening, and oppositely inclined compression coil springs interposed between said seat and the under side of the bolster.

5. In a railway car truck, a bolster, a spring seat beneath the bolster, vertically disposed compression coil springs interposed between the central portions of the bolster and seat, compression coil springs interposed

between the bolster and seat on opposite sides of said first mentioned springs, the side springs being inclined inwardly toward the centrally disposed springs.

6. In a railway car truck, a side frame member having a compression chord and a tension chord, said tension chord having a downwardly cambered intermediate portion, a bolster extending into the space between said chords, and inclined supporting springs interposed between the cambered portion of the tension chord and said bolster.

7. A side frame member for car trucks having a bolster receiving opening and a tension chord extending across the bottom of the opening, the portion of the tension chord across the bottom of said opening being downwardly cambered and having oppositely inclined spring supporting portions at opposite sides of the vertical center plane of the opening.

8. A side frame member for car trucks having a compression chord and a tension chord, spaced columns integrally connected with said chords and forming between them a bolster opening, the portion of the tension chord lying between said columns being downwardly cambered and having oppositely inclined spring supporting portions at opposite sides of the vertical center plane of the opening.

In testimony whereof I affix my signature.
FRANK W. LEWIS.
